UNITED STATES PATENT OFFICE.

VINTON E. SISSON, OF CHICAGO, ILLINOIS, ASSIGNOR TO WALTER P. MURPHY, OF CHICAGO, ILLINOIS.

REINFORCED-SHEET-METAL END WALL FOR RAILWAY-CARS.

1,387,079.

Specification of Letters Patent. Patented Aug. 9, 1921.

Original application filed December 10, 1915, Serial No. 66,127. Patent No. 1,324,569, dated December 9, 1919. Divided and this application filed July 24, 1919. Serial No. 312,898.

To all whom it may concern:

Be it known that I, VINTON E. SISSON, a citizen of the United States, residing at Chicago, in the county of Cook and State of Illinois, have invented certain new and useful Improvements in Reinforced-Sheet-Metal End Walls for Railway-Cars, of which the following is a specification.

My invention relates to the construction 10 of railway cars and more particularly box cars and has for its principal object to provide a sheet metal end wall for a railway car which will be reinforced in a novel manner so that it will be capable of withstanding 15 the cargo thrusts and other stresses and impacts to which the end wall of a car is subjected when in service.

A further object is to provide a sheet 20 steel end wall for a railway car composed of overlapping panels formed with reinforced ribs or off-sets which are so disposed on the panels that they constitute load carrying members and may be formed by a cold pressing process. Because of the latter feature, the cost of manufacturing is considerably 25 reduced.

The invention consists in the novel arrangements, constructions and combinations to be hereinafter described and claimed for 30 carrying out the above stated objects and such other objects as may appear in the following description.

The invention is illustrated in a preferred 35 embodiment in the accompanying drawings wherein—

Figure 1 is a fragmentary end elevation of the superstructure of a box car provided with the sheet metal reinforcing wall of my invention.

Fig. 2 is a vertical section taken on line 2—2 of Fig. 1.

Fig. 3 is a sectional plan taken on line 3—3 of Fig. 1.

Fig. 4 is a side view in elevation of one 45 end of the car shown in the preceding figures, and

Fig. 5 is a fragmentary plan view of the end of the car with the roof boards removed.

Like characters of reference designate like 50 parts in the several figures of the drawings.

Referring to the drawings, the corner posts of the car are shown at 10, the end sill at 11, the flooring at 12 and the side sheathing at 13. It will be understood that my

invention is not limited in its application 55 to the particular type of car shown and described.

The end of the car consists of a plurality of sheet metal panels which are preferably in vertical arrangement with their edges 60 overlapping. I have shown four of these panels designated 14, 15, 16 and 17 respectively. The upper portion of each of these panels is preferably bent over on oblique lines so as to form tapering flanges 18, 19, 65 20 and 21 respectively, shown more particularly in Fig. 5. These flanges overlap each other and are secured together by rivets 22 so as to provide in effect a continuous angle across the car on which the purlins 23 and 70 ridge pole 24 are supported. The outer ends of the flanges 18—21 rest upon and are riveted to angular brackets 25 secured to the side plates 26 of the car. The ridge pole 24 is preferably secured to the flanges 19, 20 75 and this connection is reinforced by a plate 27. 28 designates filler blocks interposed between the purlins and between the purlins and the ridge pole closing the space above the flanges 18, 19, 20 and 21 and below the 80 roof boards 29. The end of the car has the usual fascia plate 30. The lower edges of panels are formed with inturned flanges 31, 32, 33 and 34 which are preferably substantially the same as the flanges at the upper 85 edges of the sheet and are secured to the end sill 11. Each of the four panels is formed along one of its vertical edges with a hollow off-set or rib 35. This off-set portion of the panel overlaps the vertical edge of the 90 adjacent panel which is secured thereto by two lines of rivets 36 lying on opposite sides of the rib. These ribs are preferably open at opposite ends and fall short of the edges of the body portion so as to permit the horizontal edges of the panels to be bent over 95 to provide the flanges hereinbefore described. The outer edges of the panels 14, 17 are formed with angular flanges 37 which are secured to the side framing of the car, for 100 example, by bolts 38 which extend through the corner posts 10. 38^a are attaching plates riveted to the flanges 37 of the side panels and secured to the side plates 26 of the car. 39 are angular strips secured preferably, to 105 the side girths 40 of the car extending around the corner of the car and riveted to the face of the side panels as indicated at 41. The

lower edges of the flanges 37 are preferably secured to the Z shaped side sills 42 by means of gussets 43. It will be seen that the frame members of the roof are supported directly 5 on the flanges 18, 19, 20 and 21, these flanges being rigidly secured together by the rivets 22 and increasing in width toward the sides of the car makes them particularly adapted as a substitute for the end plate of the car 10 since this configuration makes them unusually strong to check weaving strains in the car roof. It will also be noted that the vertical ribs 35 extending substantially from the flooring to the roof of the car provide 15 rigid members for supporting a portion of the roof load. By extending the edges of the adjacent sheets back of the hollow rib and riveting on opposite sides thereof box girders are provided which will resist the various 20 thrusts and strain due to the shifting of the cargo or other stresses to which a car end is subjected while in service.

The end structure above described is preferably provided with a wooden inner lining 25 44 which is spaced away from the sheet metal wall by spacing strips 45, the strips and the lining being secured to the metal wall by bolts 46.

This application is a division of my application Serial Number 66,127, filed December 10, 1915, now Patent No. 1,324,569 granted December 9th, 1919.

I claim:

1. An end structure for a railway car 35 comprising a plurality of sheet metal panels in vertical arrangement one beside the other, the edges of which overlap each other, one of said overlapping edges, in each case, being formed with a pressed out rib providing a roof supporting post and the corresponding edge of the other panel being secured to said first named panel, said panels being formed on their upper and lower edges with flanges and said hollow 40 ribs falling short of said flanges, in each case.

2. An end structure for railway cars comprising a plurality of sheet metal panels which overlap each other on vertical lines, 50 one of said overlapping edges, in each case, being formed with a reinforcing rib and the corresponding edge of the other panel being secured to the first named panel on opposite sides of said rib, the edges of each 55 panel transverse to the aforesaid edges being formed with flanges and the said rib terminating short of said flanges.

3. An end structure for railway cars comprising a plurality of sheet metal panels 60 which overlap each other on vertical lines, one of said overlapping edges, in each case, being formed with a reinforcing rib and the corresponding edge of the adjacent panel being secured to the first named panel 65 on opposite sides of said rib, the upper

edge of one panel being formed with a flange which stops short of said rib and the adjacent panel being formed with a flange which overlaps the first mentioned flange.

4. An end structure for railway cars comprising a plurality of sheet metal panels which overlap each other on vertical lines, one of said overlapping edges, in each case, being formed with a reinforcing rib and the corresponding edge of the adjacent panel 70 being secured to the first named panel on opposite sides of said rib, the lower edge of one panel being formed with a flange which stops short of said rib and the adjacent panel being formed with a flange which 75 overlaps the first mentioned flange.

5. An end structure for railway cars comprising a plurality of metal sheets which overlap each other on vertical lines, one of said overlapping edges, in each case, being 80 formed with a reinforcing rib which stops short of the upper and lower edges of the sheet on which it is formed and the said upper and lower edges being bent to provide flanges adapted to be secured to the 85 framing of the car.

6. An end structure for railway cars comprising a plurality of metal sheets which overlap each other on vertical lines, one of said overlapping edges, in each case, being 90 formed with a pressed reinforcing rib which is open at opposite ends and stops short of the upper and lower edges of the sheet on which it is formed and the said upper and lower edges being bent to provide flanges 95 100 adapted to be secured to the framing of the car.

7. An end structure for railway cars comprising a plurality of metal sheets which overlap each other on vertical lines, one of 105 said overlapping edges, in each case, being formed with a pressed reinforcing rib which is open at opposite ends and stops short of the upper and lower edges of the sheet on which it is formed and the said upper and 110 lower edges of each sheet being bent to provide flanges which overlap the corresponding flanges of the adjacent sheets.

8. An end structure for railway cars comprising a plurality of metal sheets which 115 overlap each other on vertical lines, one of said overlapping edges, in each case, being formed with a hollow reinforcing rib which is open at opposite ends and stops short of the upper edge of the sheet on which it is 120 formed, the said upper edges of the sheets being bent over on oblique lines to provide flanges which increase in width toward the side of the car.

9. An end structure for railway cars comprising a plurality of metal sheets which overlap each other on vertical lines, one of said overlapping edges, in each case, being 125 formed with a hollow reinforcing rib which is open at opposite ends and stops short of 130

the upper edge of the sheet on which it is formed, the said upper edges of the sheets being bent over on oblique lines to provide flanges which increase in width toward the 5 side of the car in combination with the side and roof framing of the car, and gussets to secure said flanges to said framing.

10. In an end structure for railway cars, the combination with the side walls, roof 10 and underframing of a car, of a sheet metal end wall comprising a plurality of vertically arranged metal sheets extending substantially from the floor to the roof of the car and overlapped and secured together along vertical lines, one of the overlapping 15 edges, in each case, being formed with a pressed rib which is open at opposite ends and stops short of the upper and lower edges of the sheet on which it is formed, the upper edges of the sheets being bent over on oblique lines, overlapped, and secured together and to the side and top framing of the car and the lower edges of the sheets being formed with inturned overlapping flanges secured to the underframing of the 20 25 car.

VINTON E. SISSON.
